UNITED STATES PATENT OFFICE.

AUGUST SCHERRER, OF BIEGEL, TEXAS.

DESIGN FOR A FRAME FOR SPOOLS OR REELS.

SPECIFICATION forming part of Design No. 28,272, dated February 8, 1898.

Application filed March 29, 1897. Serial No. 629,867. Term of patent 14 years.

To all whom it may concern:

Be it known that I, AUGUST SCHERRER, a citizen of the United States, residing at Biegel, in the county of Fayette and State of Texas, 5 have invented and produced a new and original Design for Devices for Holding Spools of Wire, of which the following is a specification.

In the drawings, Figure 1 is a perspective view of my frame. Fig. 2 is a side view 10 thereof. Fig. 3 is a plan view of the frame.

The leading feature of my design consists in the general contour of the frame, including the arms *a*, which diverge toward their ends *a'*, the intermediate portion *C*, the wings *b'*, 15 departing from the end of portion *C* opposite the arms *a* at an inclined angle, and the arms

b, extending from the ends of the wings *b'* in lines parallel to that of the portion *C*, and the offset portions *b'* at the extremities of the arms *b*. A cross-bar *d* extends between the 20 arms *a*, and the extremities *a'* of said arms extend at an angle to the same and simulate the form of handles.

What I claim is—

The design for a frame for spools or reels 25 as herein shown and described.

In testimony whereof I affix my signature in presence of two witnesses.

AUGUST SCHERRER.

Witnesses:

LEE SMITH,
E. HEIMANN.
